US00D841433S

(12) **United States Design Patent** (10) Patent No.: **US D841,433 S**
(45) Date of Patent: **** Feb. 26, 2019**

(54) **TOOL CARTRIDGE CLIP**

(71) Applicant: **TRUMPF Werkzeugmaschinen GmbH + Co. KG**, Ditzingen (DE)

(72) Inventors: **Etienne Lardon**, Huenenberg See (CH); **Mathias Tweitmann**, Waedenswil (CH)

(73) Assignee: **TRUMPF Werkzeugmaschinen GmbH + Co. KG**, Ditzingen (DE)

(**) Term: **15 Years**

(21) Appl. No.: **29/611,947**

(22) Filed: **Jul. 27, 2017**

(30) **Foreign Application Priority Data**

Feb. 3, 2017 (EM) 003737873

(51) **LOC (11) Cl.** **08-05**

(52) **U.S. Cl.**

USPC **D8/354**; D15/141

(58) **Field of Classification Search**

USPC D8/14, 331, 349, 354, 366, 380-82, 385,

D8/394, 400, 404, 499; D12/400;

Assistant Examiner — Fitzgerald L Butac

(74) Attorney, Agent, or Firm — Fish & Richardson P.C.

(57) **CLAIM**

The ornamental design for a tool cartridge clip, as shown and described.

DESCRIPTION

FIG. 1 is a first perspective view of the tool cartridge clip. FIG. 2 is a second perspective view of the tool cartridge clip.

FIG. 3 is a top view of the tool cartridge clip.

FIG. 4 is a bottom view of the tool cartridge clip.

FIG. 5 is a left side view of the tool cartridge clip.

FIG. 6 is a right side view of the tool cartridge clip.

FIG. 7 is a front view of the tool cartridge clip; and,

FIG. 8 is a back view of the tool cartridge clip.

The broken lines show portions of a tool cartridge clip that form no part of the claimed design.

1 Claim, 3 Drawing Sheets
